(57) **CLAIM**

The ornamental design for a mouth guard, as shown and described.

DESCRIPTION

FIG. 1 is a front perspective view of the mouth guard; FIG. 2 is a rear perspective view of the mouth guard; FIG. 3 is a front elevation view of the mouth guard; FIG. 4 is a top plan view of the mouth guard; FIG. 5 is a rear elevation view of the mouth guard; FIG. 6 is a side elevation view of the mouth guard; and, FIG. 7 is a bottom plan view of the mouth guard. The broken lines in the drawings illustrate portions of the mouth guard that form no part of the claimed design.

1 Claim, 7 Drawing Sheets
